APPARATUS FOR FIRMING AND FINISHING
LEATHEREarle Wilson, Chicago, Ill., assignor to The
American Oak Leather Co., Cincinnati, Ohio,
a corporation of Ohio

Application May 17, 1935, Serial No. 22,926

3 Claims. (Cl. 69—1)

This invention relates to an improved apparatus for firming and finishing leather, and has for one of its principal objects the provision of means whereby sole leather and the like can be made firm and have a desirable finish applied to the surfaces in a novel and more satisfactory manner while, at the same time, eliminating some of the disadvantages attendant upon prior processes and devices.

One of the important objects of this invention is to provide a means whereby pieces of leather, particularly cut stock for sole leather and the like, can be firmed and finished, while, at the same time, the desired shape, size and dimensions of the piece of leather or other stock is satisfactorily retained.

Another object of the invention is to eliminate the use of rollers for such a firming and finishing operation and also to eliminate the necessity of operating on large pieces wherein no effort was made to control the shape of the piece.

Another and still further important object of the invention is to provide an apparatus for such a firming and finishing operation on leather which will automatically prevent excessive reduction in thickness, thereby enhancing the value of the finished product.

Other and further important objects of the invention will be apparent from the disclosures in the accompanying drawing and following specification.

The invention, in a preferred form, is shown in the drawing and hereinafter more fully described.

In the drawing:

Figure 1 is a top plan view of the improved and preferred apparatus in which the firming and finishing operations of this invention are to be carried out.

Figure 2 is a composite front view of the apparatus.

Figure 3 is a sectional view taken on the line 3—3 of Figure 1, looking in the direction indicated by the arrows and showing a portion of the face in dotted lines.

Figure 4 is a sectional view on the line 4—4 of Figure 1, showing a portion in dotted lines.

Figure 5 is a perspective view, illustrating a representative piece of sole leather or the like finished in the apparatus and in accordance with the principles of this invention.

As shown in the drawing:

The reference numeral 10 indicates generally the bed-plate or base of the improved leather firming and finishing device of this invention.

the same having mounted thereon a pair of fixed side rails or the like 12 and 14 respectively which are held in position on the bed-plate by means of bolts or rivets 16.

Adapted to cooperate with these fixed side rails and to form a sort of rectangular frame therewith is a pair of movable rails 18 and 20 respectively which are slidably mounted on the base-plate and which are preferably hinged together at 22.

Positioned inside the fixed rails 12 and 14 is a portion of a die or shaping member 24 which, in this particular instance, is L-shaped to correspond with two sides 26 and 28 of a piece of leather 30 to be finished in the die, which piece 15 of leather is shown at Figure 5.

Also adapted to cooperate with the relatively fixed element 24 is a relatively slidable element 32 also approximately L-shaped as shown in Figure 1 and having end portions 34 and 36 which fit into corresponding notches or offset portions in the element 24. Obviously, these die elements 24—32 can be of any desired shape or size so as to accurately conform to any particular piece of leather or other material which has to be treated or otherwise operated upon in the apparatus.

In order to allow of free insertion and removal of the piece of leather 30 or the like from the forming dies, the movable element 32 is adapted to be shifted into position by means of handle-operated cams 38, 40 and 42 respectively which operate against the movable side rails 18 and 20 so as to push the same inwardly, forming the desired area and shape for the piece of leather to be treated in the dies. Guard elements 44 are positioned over the ends of the cam structures both as safety elements and also to retain the rails 18 and 20 in proper position on the bed-plate 10. Operating handles for the cams are illustrated at 46, and the cam 38 is preferably conjointly operated with the cam 40 by means of a link 48. A fixed element 50 is provided adjacent the inner end 36 of the element 32 to assure of a better co-operation between the moving parts. This has a cam face as shown.

As shown in Figure 2, a finishing plunger or similar structure 52 adapted to operate upon a piece of leather or the like 30 placed in the dies 24—32 is mounted on a punch press element or the like 54 for a punching, flattening, and finishing operation on leather in the dies and on the bed-plate 10.

Either the plunger or the plate can be heated, if desired, preferably by electrical means so that the temperature can be adequately controlled.

and this heating is utilized to produce desired color gradations in the finished product.

The upper surface of the bed-plate 10 upon which the leather is placed with the grain face down is of smooth, relatively soft material such as brass or the like, and the hammering or punching operation of the element 52 on the leather produces a correspondingly smooth finish on the grain face of the leather which is in contact 10 with the bed-plate. Heretofore, when this has been accomplished by rollers, the leather has been undesirably flattened and reduced in thickness, but with the dies of this invention holding the same in proper shape and providing against lateral expansion, this flattening and also any undesirable pushing out of shape is avoided, and the original thickness of the leather is maintained to quite a considerable degree. Inasmuch as the 15 price of this sole leather is based almost entirely upon its thickness, this maintenance of thickness during this firming and finishing operation constitutes a very important factor.

Whenever it is desired to insert a piece of leather to be firmed or finished in the device, the 20 handles 48 are so operated that the cams allow of an outward motion of the elements 18 and 28 and a corresponding outward movement of the die structure 32. This allows of a ready insertion of the correspondingly shaped piece of leather 30 into the die structure and onto the bed-plate 10. The handles 48 are then operated to cause the cams to close the dies, after which the punch press element 52 is put into motion for a desired 35 number of hammering or thumping operations on the leather which renders the same firm and also produces a desired gloss or finish on the grain face of the leather which is against the smooth and relatively soft upper face of the bed-plate 10. The close fit of the die structures around the 40 periphery of the piece of leather prevents any undue spreading or deforming from the desired shape and also incidentally prevents undesirable thinning out of the leather.

It will be evident that herein is provided a 45 different process for such firming and finishing operations on leather or the like which enables the application of this process directly to small pieces or cut stock production and allows for the con-

trol of products manufactured from sole leather creating desirable physical properties on those items. The fixture or mold can obviously be of any shape to fit the product to be firmed and finished.

I am aware that many changes may be made and numerous details of construction varied throughout a wide range without departing from the principles of this invention, and I, therefore, do not purpose limiting the patent granted hereon otherwise than as necessitated by the prior art.

I claim as my invention:

1. A firming and finishing apparatus for leather, comprising a smooth-faced bed-plate, a 15 set of dies removably and slidably mounted on the bed-plate, and a leather finishing element reciprocatively mounted above the bed-plate and the dies, together with lateral supports for the die members, certain of said supports being fixed 20 on the bed-plate and others being movably mounted on the plate, a wedge on the plate cooperating with the die support, and manually-operated cams for shifting the movable supports into desired operating position.

2. A firming and finishing apparatus for leather, comprising a smooth-faced bed-plate, a set of dies removably and slidably mounted on the bed-plate, and a leather finishing element reciprocatively mounted above the bed-plate and 30 the dies, together with lateral supports for the die members, certain of said supports being fixed on the bed-plate and others being movably mounted on the plate, and manually-operated 35 cams for shifting the movable supports into desired operating position, and combined guards and support-retaining elements on the cams.

3. A firming and finishing apparatus for leather, comprising a smooth-faced bed-plate, a set of dies removably and slidably mounted on 40 the bed-plate, and a leather finishing element reciprocatively mounted above the bed-plate and the dies, together with lateral supports for the die members, certain of said supports being fixed on the bed-plate and others being movably mounted 45 on the plate, and a pivotal connection between the movably mounted supports.

EARLE WILSON.
